UNITED STATES PATENT OFFICE

HENRY J. MACKIN, OF CHICAGO, ILLINOIS

VENETIAN BLIND

Application filed February 5, 1927. Serial No. 166,092.

This invention relates to a shade, and particularly to a shade of the type commonly called a "Venetian blind." It has for one object to provide a shade which may be raised or lowered and in which an automatic locking device is provided so that the shade is automatically locked in any selective position to which it is moved. Another object is to provide positive and automatic means, 10 in a shade of the type mentioned, whereby the shade will be raised or lowered equally throughout its width. Another object is to provide a shade of the Venetian type in which the slats are not permanently attached to 15 the structure or to each other, and in which they can be readily removed without movement or alteration of the main assembly. Other objects will appear from time to time in the specification and claims.

20 The invention is illustrated more or less diagrammatically in the accompanying drawings, in which

Figure 1 is a side elevation;

25 Figure 2 is a vertical transverse cross-section taken on the line 2-2 of Fig. 1;

Figure 3 is a horizontal cross-section taken on line 3-3 of Fig. 1, on an enlarged scale;

30 Figure 4 is a detailed view of the automatic locking mechanism shown in elevation on an enlarged scale;

Figure 5 is a vertical cross-section taken on line 5-5 of Fig. 4;

35 Figure 6 is a horizontal cross-section taken on line 6-6 of Fig. 1, on an enlarged scale;

Figure 7 is a horizontal cross-section taken on line 7-7 of Fig. 1, on an enlarged scale;

40 Figure 8 is a fragmentary vertical cross-section taken on line 8-8 of Fig. 1, showing on an enlarged scale the means for tilting the slats;

Figure 9 is a view generally similar to Fig. 8, showing the slats in the tilted position;

45 Figure 10 is a vertical cross-section taken on line 10-10 of Fig. 2, showing on an enlarged scale the connections at the bottom of the blind;

Figure 11 is a cross-section taken on line 11-11 of Fig. 10;

50 Figure 12 is a detailed sectional view showing

ing the friction engaging element which is positioned at the top of the blind.

Like parts are designated by like characters throughout.

A is a window frame in which a window A¹ 55 may be positioned. B is a channel partially covered on its outer face as at B¹, and provided with outwardly extending flanges B² which bound a slot B³. C is a bearing member held by a pin C¹ which is positioned in the flanges B². C² is a shaft held at one end in the bearing member C and at its other end in the bearing member C³. C⁴ is a pulley mounted on the shaft C².

One of the channel members B is mounted, 65 preferably vertically, on each side of the window frame. One of the bearing members just described is mounted inside of each channel adjacent its lower end.

D is a bearing member mounted in the 70 channel member B adjacent its upper end, held in position therein by pins or bolts D¹. The bearing member is provided with an enlarged end D² within which ball bearings D³ may be positioned. E is a shaft journaled in 75 the bearing portion D, carrying at its outer end a bushing E¹ from which a sprocket wheel E² is fixed, and being attached at its inner end to an enlarged shaft portion E³. One of such bearings, shafts and sprocket wheels is 80 mounted at each end of the blind, each of the wheels lying within one of the channels. E⁴ is a shaft member, preferably hollow, provided at each end with slots E⁵ within which pins E⁶ mounted in the shaft sections E³ may 85 extend.

F is a friction member formed in a generally semi-circular shape, provided at each end with an extension F¹ F². F³ is a similar member provided with corresponding extensions F⁴ F⁵. The extensions F¹ F² are preferably joined in adjustable position by a screw F⁶. The members F F³, a pair at each side of the blind, are positioned about the bearing portions D² and engage them 90 with a greater or less friction, depending upon the adjustment of the screws F⁶. F⁷ F⁸ are slat members, each of which is attached at each of its ends to the friction members F F³ by means of screws F⁹. F⁹ is a

shield member engaging each of the slat members F^7 and extending substantially from end to end of the composite shaft $E^3 E^4$, and serving to unite slats F^7 and to form in effect with them a section upon a slat member.

10 G are slat-holding members, preferably tapes, fastened at their upper ends to the composite slat F^7 and at their lower ends to the slat H which will be described below. Between adjacently placed tapes G are cross-tapes G^1 .

15 H is a bottom slat member extending throughout the width of the blind, and having at each end a perforation H^1 within which is positioned a shaft H^2 which carries at its free end a block H^3 . H^4 is a roller freely mounted upon the shaft H^2 so as to rotate thereabout. The tapes G are at their 20 bottom ends fastened to this slat member H .

25 I is a cord provided at one end with a weight or handle I^1 , extending upwardly about a pulley I^2 , passing about the composite slat member F^7 and being fastened thereupon to a screw or pin I^3 . I^4 is a similar cord fastened also to the pin I^3 , passing across the upper surface of the composite slat F^7 , passing thence downwardly along the cord I and terminating at its lower end in a weight or handle I^5 .

30 J is a pulley supporting frame mounted on one of the channel members B , preferably adjacent its upper end. J^1 is an opening in the channel member B . J^2 is a pulley mounted in the frame J . J^3 is a slot in the member 35 B . J^4 is a locking lever provided with an inwardly extending hook part J^5 , which extends inwardly through the slot J^3 and may engage the sprocket wheel E^2 to lock it. The lever J^4 is pivotally supported in the frame 40 J at J^6 . It is provided with a smaller bent extension J^7 . Its mounting and its proportions are such that when free to move it normally tends to fall into the position shown in full lines in Fig. 5. J^8 is a second locking lever pivoted also on the frame member J at the point J^9 . It is provided with an upper, laterally bent extension J^{10} which may be brought into contact with the portion J^7 of the lever J^4 . The lever J^8 is provided at its 45 lower end with a loop or eyelet J^{11} .

50 K is a cord fastened at one end to an eyelet K^1 fixed on the slat H . It passes through the pulley ring or eyelet K^2 , which is positioned on the window frame A . It passes thence upward along the channel member B but outside of it, passing through the eyelet J^{11} , over the pulley J^2 , and thence downward inside the channel member B , and is fastened to the sprocket chain L . This chain L is fastened 55 to the block H^3 , passes upward inside of the channel B , over the upper sprocket wheel E^2 , downward inside the channel B about the lower pulley or sprocket wheel C^4 , upward, and is finally fastened to the bottom of the 60 block H^3 . An identical chain and sprocket 65

wheel assembly is formed on the opposite side of the blind but there is only a single cord K . The sprocket chain, as shown particularly in Figs. 10 and 11, need not be uniform, several sorts of chains being used in 70 the same assembly.

75 L^1 is a slat provided at each end with an extension L^2 which normally lies between the flanges B^2 of the channel member B . L^3 is a rubber or slat cushioning member extending about the end portion L^2 . L^4 is a slat similar to the slat L^1 but without the extensions L^2 . Throughout the vertical height of the blind 80 these slats are laid one on each of the cross-tapes G^1 , the slats being alternated so that there is first a slat without end extensions and then a slat with end extensions. This proportion is not fixed and a greater or less number of slats with end extensions might be 85 used.

85 The use and operation of the invention are as follows:

90 The parts are normally assembled as shown in Figs. 1 and 2, and in this position the locking lever J^4 lies as shown in full lines in Fig. 5, locking the sprocket wheel E^2 and thus locking the composite shaft $E^3 E^4$ against movement and preventing raising or lowering of the blind. When it is desired to move the blind either up or down, the cord 95 K is pulled, tension on this cord rotates the lever J^8 into the position shown in dotted lines in Fig. 5; this causes a corresponding rotation of the lever J^4 , also to the dotted line position of Fig. 5, and thus unlocks the 100 sprocket wheel E^2 and permits movement of the shade. Further pulling of the cord K raises the bottom slat H and raises the blind as a whole. The movement either to raise or lower the blind is the same. In each case the cord K must be pulled, and in each case any pulling tension on the cord unlocks the 105 sprocket wheel. The moment the tension is reduced the locking parts fall automatically into locking position and prevent further 110 movement of the blind.

115 When it is desired to tilt the slats of the blind, the cord I or the cord I^4 is manipulated. In order to tilt the parts from the position shown in Fig. 8 to that shown in Fig. 9, the cord I is pulled. This raises one edge of the composite slat F^7 into the position shown in Fig. 9, and since it alters the adjustment of the tapes G it moves all of the slats correspondingly. To return the parts to the former position a reverse movement is given by pulling the cord I^4 .

120 When the blind is in the raised position, it can normally be lowered only by manipulation of the controlling cords; that is to say, by manipulating or pulling in one direction or the other on the cord K . The blind can, however, be raised by hand by merely pushing upward. The effect of this upward push 125 is transmitted through the cord K and the 130

locking mechanism is operated so as to lock the blind in the new raised position as soon as the raising is stopped.

I claim:

- 5 1. In a blind, raising and lowering means for such blind, and latching means for such raising and lowering means, adapted to hold the blind in any position of vertical adjustment irrespective of the means by which it is moved to such position of adjustment. 70
- 10 2. In a blind, raising and lowering means for such blind, latching means for such raising and lowering means adapted to hold the blind in any position of vertical adjustment irrespective of the means by which the blind is moved to the position of adjustment and automatic means for holding the slats of such blind longitudinally horizontal at all positions of vertical adjustment of said blind. 75
- 15 3. As a new article of manufacture a blind mounted for vertical movement, raising and lowering means for such blind and a latching means governed by such raising means and adapted to latch such blind in any position of vertical adjustment, such latching means when in the locking position holding the blind against lowering and free for raising the blind irrespective of the position of such latching means. 80
- 20 4. As a new article of manufacture a blind mounted for vertical movement by direct manipulation of the blind itself, additional raising and lower means for such blind and a latching means governed by such raising means and adapted to latch such blind in any position of vertical adjustment, such latching means when in the locking position holding the blind against lowering and free for raising the blind irrespective of the position of such latching means. 85
- 25 5. As a new article of manufacture a Venetian blind, automatic means holding said blind free for vertical movement, raising and lowering means for such blind and an automatic latching means governed by such raising means and adapted automatically to latch such blind in any position of vertical adjustment, such latching means when in the latching position holding the blind against lowering and free for raising the blind irrespective of the position of such latching means. 90
- 30 6. As a new article of manufacture, a blind, automatic holding means holding said blind free for vertical movement by direct manipulation of the blind itself, raising and lowering means for such blind and an automatic latching means governed by such raising means and adapted automatically to latch such blind in any position of vertical adjustment, such latching means when in the latching position holding the blind against lowering and free for raising the blind irrespective of the position of such latching means. 95
- 35 7. As a new article of manufacture, a Venetian blind, automatic holding means for holding the blind free for vertical movement by direct manipulation of the blind itself, raising and lowering means for such blind and an automatic latching means governed by such raising means and adapted automatically to latch such blind in any position of vertical adjustment, such latching means when in the latching position holding the blind against lowering and free for raising the blind irrespective of the position of such latching means. 100
- 40 8. In a blind, an upper member and a lower member, intermediate spaced members, means for raising and lowering such blind including means for raising and lowering the lower member, such means including flexible members extending throughout the greatest possible length of such blind and being fastened to such lower member, chains and sprocket wheels for such chains adapted to engage them, said sprocket wheels being located at the top and bottom of such blind assembly, means for moving such chains to raise and to lower the lower member and additional means for automatically latching such sprocket wheels in any position against lowering and free for raising. 105
- 45 9. In a blind, an upper member and a lower member, intermediate spaced members, means for raising and lowering such blind including means for raising and lowering the lower member, such means including flexible members extending throughout the greatest possible length of such blind and being fastened to such lower member, chains and sprocket wheels for such chains adapted to engage them, said sprocket wheels being located at the top and bottom of such blind assembly, means for moving such chains to raise and to lower the lower member and additional means for automatically latching such sprocket wheels in any position against lowering and free for raising. 110
- 50 10. In a blind, an upper member and a lower member, intermediate spaced members, means for raising and lowering such blind including means for raising and lowering the lower member, such means including flexible members extending throughout the greatest possible length of such blind and being fastened to such lower member, chains and sprocket wheels for such chains adapted to engage them, said sprocket wheels being located at the top and bottom of such blind assembly, those at the top being joined together so that they rotate in unison, means for moving such chains to raise and to lower the lower member and additional means for automatically latching such sprocket wheels in any position against lowering and free for raising. 115
- 55 11. As a new article of manufacture, a Venetian blind, automatic holding means for holding the blind free for vertical movement by direct manipulation of the blind itself, raising and lowering means for such blind and an automatic latching means governed by such raising means and adapted automatically to latch such blind in any position of vertical adjustment, such latching means when in the latching position holding the blind against lowering and free for raising the blind irrespective of the position of such latching means. 120
- 60 12. As a new article of manufacture, a Venetian blind, automatic holding means for holding the blind free for vertical movement by direct manipulation of the blind itself, raising and lowering means for such blind and an automatic latching means governed by such raising means and adapted automatically to latch such blind in any position of vertical adjustment, such latching means when in the latching position holding the blind against lowering and free for raising the blind irrespective of the position of such latching means. 125
- 65 13. As a new article of manufacture, a Venetian blind, automatic holding means for holding the blind free for vertical movement by direct manipulation of the blind itself, raising and lowering means for such blind and an automatic latching means governed by such raising means and adapted automatically to latch such blind in any position of vertical adjustment, such latching means when in the latching position holding the blind against lowering and free for raising the blind irrespective of the position of such latching means. 130

11. In a blind, an upper member and a lower member, intermediate spaced members, means for raising and lowering such blind including means for raising and lowering the lower member, such means including flexible members extending throughout the greatest possible length of such blind and being fastened to such lower member, chains and sprocket wheels for such chains adapted to engage them, said sprocket wheels being located at the top and bottom of such blind assembly, those at the top being joined together so that they rotate in unison, means for moving such chains to raise and to lower the lower member and additional means for automatically latching such sprocket wheels in any position against lowering and free for raising, and automatic means for maintaining such blind horizontal at all positions of vertical adjustment.
12. In combination in a flexible blind, a plurality of shutter members, flexible means for holding them in position, means for tilting them in unison, means for raising the blind and automatic latching means whereby the blind may be latched in any adjusted position, such raising means including a plurality of hoisting members joined for operation in unison, a single actuating means, a latch adapted to latch such hoisting means and to be unlatched by manipulation of such actuating means to free the mechanism for hoisting thereafter, such latch being automatic and adapted to move at once to the latching position when the actuating means is not in use, and to free the mechanism for raising movement of the blind at all times.
13. In a Venetian blind formed of a plurality of slats, flexible members adapted to support such slats in spaced relation, means for raising the blind including a plurality of hoisting means and a positive connecting means between the two whereby they operate in unison uniformly, actuating means for operating such hoisting means and a latch adapted automatically to latch such hoisting means in any position and thereby to latch the blind in any adjusted position, such actuating means being adapted to unlatch said latch at the commencement of the actuating operation, such latch being adapted automatically to assume the latching position upon the termination of the actuating operation, and to free the mechanism for raising movement of the blind at all times irrespective of the position of the latch.
14. In combination in a blind, a plurality of imperforate slats, a holding assembly for such slats, including members extending generally lengthwise of such blind, and spaced connecting members between such first mentioned members, the slats being supported by such connecting members and freely removable from them and means for raising and lowering the blind, located outside the limits of the slats and entirely disconnected therefrom, whereby the slats are left intact to preserve their full strength.
15. In combination in a blind, a plurality of imperforate slats, a holding assembly for such slats, including members extending generally lengthwise of such blind, and spaced connecting members between such first mentioned members, the slats being loosely supported by such connecting members and freely removable from them and means for raising and lowering the blind, located outside the limits of the slats and entirely disconnected therefrom, whereby the slats are left intact to preserve their full strength.
16. In combination in a blind, a plurality of imperforate slats, a holding assembly for such slats, including supporting parts adapted to carry such slats, the slats being freely removable therefrom without disturbance of the blind as a whole and means for raising and lowering the blind, located outside the limits of the slats and entirely disconnected therefrom, whereby the slats are left intact to preserve their full strength.

Signed at Chicago, county of Cook and State of Illinois.

HENRY J. MACKIN.
